In Great Britain March 5, 1944

5-Claims. (Cl. 42—1).

1

This invention relates to automatic firearms of the short barrel-recoil type and has for its object to provide novel means for effecting the breech action.

According to this invention, in a weapon of the type referred to, the movement of the breech bolt for reloading is effected by a hood or inertia-actuated member which is locked in a position covering the breech in the firing position, and which is unlocked at or near the end of the recoil and is driven in a rearward direction by a spring mounted on the magazine tube and compressed by the recoil, and carries the bolt with it by means of a loose coupling.

The bolt is preferably locked in the firing position independently of the hood and is unlocked during the rearward travel of the hood.

Further features of the invention will become apparent from the following description given with reference to the accompanying drawings which illustrate the invention as applied to a shot gun and rifle.

In the drawings—

Figure 1 is an elevation and Figure 2 is a plan of part of a shot gun;

Figures 3 to 5 are partial sectional elevations with parts omitted of the shot gun, illustrating the movement of the hood and breech bolt;

Figure 6 is a sectional elevation, illustrating the action of the cartridge spoon;

Figures 7, 8 and 9 are details of the spoon and associated parts;

Figures 10, 11 and 12 are details of the hood locking means;

Figure 13 is an elevation and Figure 14 a sectional elevation of the breech bolt;

Figure 15 is a sectional elevation and Figure 16 is an inverted plan of the locking piece;

Figure 17 is a rear elevation of the bolt;

Figures 18, 19 and 20 are respectively an end elevation, elevation and plan of the crutch;

Figures 21 and 22 are details showing hood recoil buffering means;

Figure 23 is an elevation of the hood;

Figure 24 is an elevation of the double nut on the end of the magazine tube;

Figures 25 and 26 are details of members shown in Figure 24;

Figures 27 and 28 are elevations of a breech bolt suitable for a rifle, respectively in locked and unlocked position and;

Figure 29 is a plan of breech bolt of Figures 27 and 28.

Referring first to Figures 1, 2 and 3 to 5, a cradle or breech frame receiver 1 supports the

recoiling barrel extension 2, to which the barrel 3 is fixed. A tubular magazine 4 is attached to the receiver 1 and projects forward parallel to the barrel 3. A cover 5 is provided over the magazine 4 and is held in place by a double nut 6. A lug 7 on the barrel 3 slides along the magazine 4 to assist in guiding the barrel 3 during its recoiling and return movements. A ring 8 is slidable on the magazine 4 and is rigidly coupled to the lug 7 by links 9, one on each side. A recoil spring 10 surrounds the rear part of the magazine 4 and on recoil is compressed between the ring 8 and a loose ring 11, which rests against the receiver 1.

15 The breech is normally covered by a hood 12, which can slide longitudinally on the barrel extension 2, pins 13 on either side of the hood 12 engaging in slots 14 in the barrel extension 2. The hood 12 has two projections 15 at the front near the lower edges of its sides to cooperate with a crutch shown separately in Figures 18, 19 and 20. This crutch comprises a ring 16 to slide on the magazine 4, two arms 17 extending rearwards from the ring 16 and feet 18 on the rear ends of the arms 17, which feet press on the projections 15 of the hood 12. When the barrel 3 recoils, the lug 7 compresses a master spring 19 against the ring 16, which tends to drive the hood 12 rearwards.

20 During firing and the first part of the recoil, the hood 12 is held in place by a lever 20 pivoted on a pivot 21 and provided with a projection 22, which engages behind the rear end of the hood 12.

The manner in which the lever 20 is mounted may be seen best from Figures 10 to 12, in conjunction with Figures 1 and 2. A plug 23 is mounted to slide vertically in the receiver 1 and is urged upwards by a spring 24. The plug 23 is pivoted by a pin 25 to the lever 20 and holds the latter normally in the locking position of Figure 1. A chamfered head 26 on the plug 23 is engaged by a part of the barrel extension 2 which depresses the plug 23 on recoil, at the appropriate time to release the hood 12 by the consequent downward movement of the lever 20.

25 During the recoil, the master spring 19 is compressed and drives the hood 12 backwards as soon as the lever 20 releases it. A thumb piece 28 on the lever 20 provides for release by hand when required.

The breech bolt 29 is movable longitudinally inside the hood 12 and is shown separately in Figures 13 to 17. A locking piece 30 (Figures 15 and 16) is pivoted at 31 at the front end of

the bolt on its under side and has two cheeks 32 partly embracing the sides of the bolt. A spring 33 fixed at 34 to the locking piece 30 has a toe 35 pressing against the body of the bolt 29 near the forward end to urge the locking piece 30 downwards, in which position the latter engages a notch in the barrel extension 2 and so locks the bolt in the position shown in Figure 4.

Each cheek 32 has a cam slot 36 to engage the pin 13 projecting inwards from the respective side of the hood 12. The forward part of the slot 36 is horizontal and the rear part slopes downwards. After the hood 12 has moved a short distance rearwards the pins 13 come to the downwardly sloping portions of the slots 36 and raise the locking piece 30. By the time the pins 13 reach the rear ends of the slots 36 the bolt 29 is unlocked, and the hood 12 carries the bolt 29 back with it by virtue of its kinetic energy against the effect of a recuperator spring 37 (Figure 4). The bolt 29 has a recess 38 for the reception of the forward part of the spring 37. The spring 37 surrounds a rod 39 which assists in the ejection of the spent cartridge.

A firing pin 40 is slidably mounted in the bolt 29 and has a depending rear portion 41. A ridge 42 at the rear end of the locking piece 30 engages the front of the portion 41 when the bolt 29 is unlocked and so locks the firing pin 40 in its retracted position. In moving to the bolt-unlocking position the ridge 42 of the locking piece 30 retracts the firing pin 40 prior to locking it. Referring more particularly to Figures 6 to 9, as the bolt 29 reaches its rearmost position, a depending rear portion of the firing pin, as herein-after set forth, or the underside of the bolt 29 engages the sloping end of a lever 43, pivoted at 44, which depresses through a link 45 the rear end of a spoon feed arm 46 pivoted at 47 and so swings the front end of the arm up against the pressure of a spring 48. In this position a safety catch 27 carried by the lever 43 engages in a recess in the sear of the trigger mechanism thereby locking it.

A spring lever pawl 49 in the side of the receiver 1 engages in a ring 50 on the underside of the arm 46 and holds the arm 46 in its raised position (as shown in broken lines in Figure 6) during the first part of the return of the hood and bolt. Meanwhile the cartridge 51 carried by the spoon arm 46 is engaged by an extractor 52 on the side of the bolt 29, and is pushed into the chamber. A raised portion 49a at the front end of the lever pawl 49 is engaged by a depending lug 53 on the side of the hood 12 (see Figure 23) when the cartridge 51 has partly entered the chamber. The lever 49 is thereby tilted to release the pawl from the ring 50 on the spoon arm 46, and the arm is returned to its lower position (as shown in full lines in Figure 6) by the spring 48 ready to receive a fresh cartridge in the spoon.

The spoon arm 46 carries near its front end a spoon 54, pivoted to the arm 46 at 55, adapted to receive the cartridge. The position of the pivot 55 and the distribution of weight in the spoon 54 are so adjusted that when there is no cartridge in the spoon 54 the rear end 56 of the same occupies the position shown in Figure 6. Thus if the arm 46 is raised while the spoon 54 is empty, the rear end 56 projects into the path of the bolt 29 and arrest it in the position shown in the dotted lines in Figure 6. When the spoon 54 carries a cartridge, the rear end 56 is depressed out of the path of the bolt 29. In this

way the breech is kept open when both chamber and magazine are empty.

The hammer and trigger gear are of normal construction, but the cocking of the hammer 57 is effected in two stages. A roller 58 is mounted on the barrel extension 2, which half cocks the hammer 57 (as shown in Figure 4) during the recoil. Cocking is completed by the depending rear portion 41 of the firing pin 40 during the rearward travel of the bolt 29.

The impact of the hood on its return to the firing position is taken, through the crutch 17, by the spring 19 thereby converting this element into a forward buffer controlling the run out.

15 The rod 39 protrudes from the face of the bolt 29, when the latter reaches its rearmost position and acts as an ejector. Another ejector consisting of a spring-urged plunger projecting from the face of the bolt is mounted in a boring in the upper right hand side of the bolt. Figure 5 shows the position at the moment of ejection of the spent cartridge 51.

20 Figure 4 shows the position when the barrel 3 and barrel extension 2 have commenced the recoil and have half cocked the hammer 57, but before the hood 12 has been unlocked.

25 Figure 5 shows the position when the hood 12 has unlocked the bolt 29 by the sliding movement of the pins 13 in the cam slot 36 and the hood 30 12 has carried the bolt 29 rearwardly to the cartridge ejecting position. The hammer 57 has been fully cocked by the depending rear portion 41 of the firing pin 40.

30 Figure 3 shows the position when the hood 12 and bolt 29 have reached their rearmost position, the cartridge 51 having been raised by the spoon arm. For the sake of clarity the spoon arm and associated mechanism are omitted from Figures 3 to 5.

35 40 Referring now to Figures 21 and 22 the top of the hood 12 has a resilient strip 59 secured thereto by a screw 60, the free end of the strip projecting down through a slot in the top of the hood 12 and being adapted to slide in a groove 61 in the top of the barrel extension 2. The end of the groove 61 is undercut at 62. When the hood 12 reaches the end of its rearward movement, the strip 59 engages in the undercut portion 62 thereby arresting the travel of the hood 50 12 and cushioning the shock.

45 As shown in Figures 1, 2 and 23, the hood 12 may be provided with thicker portions 63 to augment the weight of the hood and provide a grip for hand movement of the hood when required.

50 55 To make the mechanism suitable for a rifle relying on a box magazine for its supply of ammunition, certain modifications are required, mainly to the bolt and the locking piece. These will now be described with reference to Figures 27 to 29. The most evident change is the location of the locking piece on the top of the bolt.

55 60 The bolt 64 has two lugs 65 on each side near the two ends to engage guide grooves in the barrel extension. The locking piece 66 comprises two side portions 67 to fit recesses 68 in the bolt 64 and a flat portion 69 uniting the side portions and lying on top of the bolt 64 when in the unlocking position (Figure 28). The locking piece 66 is pivoted at 70 on the bolt 64 near its front end. Screws 71 engage by their points grooves (not shown) in the sides of the bolt 64 to limit the movement of the locking piece 66. Lugs 72 on the sides of the locking piece 66 are in alignment with the lugs 65 in the unlocking position. 75 When the locking piece 66 is in its raised or lock-

ing position (Figure 27) to which it is urged by the spring 73 bearing on top of the bolt 64 the lugs 72 rest against shoulders in the barrel extension to lock the bolt 64 in the firing position. At the same time the rear end of the locking piece 66 bears against a shoulder at the top of the barrel extension.

The movement of the locking piece 66 into its locking and unlocking position is effected in the same way as in the shot gun by means of grooves 74 in the side portions 67 of the locking piece 66.

Referring now to Figures 24 to 26, these show details of the construction of the double nut 6 which serves the dual purpose of holding the magazine cover 5 in position against the receiver 1 (see Figures 1 and 2) and of adjusting the compression of a front buffer spring 82. The double nut 6 consists of an inner nut 75 which screws onto the magazine 4, and the inner end of which bears against the buffer spring 82, and an outer nut 76 which screws on to the inner nut 75. The rear end of the nut 76 is provided with a flange 77 the rear face of which carries two points or teeth 78 carried on the end of spring members 79. Secured to the front face of the magazine cover 5 is a ring 80 having therein a number of perforations 81 into which the teeth 78 are adapted to engage. In this way unintentional turning of the nut 76 is prevented.

Referring again to Figure 3, the cartridges 51 in the magazine tube 4 are moved into the spoon by means of a follower 83 urged by a spring 84. To prevent the follower passing into the receiver 1 when the magazine tube 4 is empty, the follower 83 is provided with a split spring band 85 adapted to spring into a groove 86. If desired the follower 83 may be provided with a rod 87 adapted to protrude through the double nut 6 to give an indication of how many cartridges the magazine contains.

We prefer that the springs used in the firearm should be made of steel containing about 2.5 to 2.75% of beryllium since this material has been found to have greatly superior resistance to repeated percussion.

What we claim is:

1. An automatic firearm of the recoiling barrel type in which there is a breech frame, a receiver on which the breech frame is slidably mounted and a bolt in said breech frame, in combination with a hood slidably mounted on the breech frame, means for locking the hood to the receiver in the firing position where it covers the breech, a magazine tube and a spring thereon compressed by the recoil and adapted to drive the hood rearwardly, means on the breech frame to unlock said locking means at or near the end of the recoil, a loose coupling connecting the bolt and the hood, whereby rearward movement of the hood relative to the breech frame carries the bolt rearwards within the breech frame to the reloading position, and a recuperator spring compressed on the rearward travel of the hood and bolt which serves to return both these members to the firing position.

2. An automatic firearm of the recoiling barrel

type according to claim 1 in which the loose coupling has pins projecting inwards from the hood, in combination with a locking piece having side portions for locking the bolt in the firing position independently of the hood, said side portions having cam grooves which engage the coupling pins, the cam grooves having longitudinal portions to permit relative movement of the hood and the bolt during the recoil and sloping portions to effect unlocking of the bolt during the rearward travel of the hood.

3. An automatic firearm of the recoiling barrel type according to claim 1 in which the loose coupling has pins projecting inwards from the hood, in combination with a locking piece comprising side portions pivotally mounted near the front face of the bolt which engages a notch in the breech to lock the bolt to the breech in the firing position, said side portions having cam grooves which engage the coupling pins, the cam grooves having longitudinal portions to permit relative movement of the hood and the bolt during the recoil and sloping portions to effect pivoting of said locking piece out of engagement with the said notch to effect unlocking of the bolt during the rearward travel of the hood.

4. In an automatic firearm of the recoiling barrel type according to claim 1, the combination of a receiver, the magazine tube being mounted thereon, a master spring surrounding the magazine tube, a lug secured to the barrel and surrounding the magazine tube, a crutch comprising a ring surrounding the magazine tube and two arms having feet adapted to engage projections on the front of the hood, said master spring being located between said lug and said crutch ring so that the master spring is compressed on recoil and serves to drive the hood rearwardly when the hood is unlocked.

5. In an automatic firearm of the recoiling barrel type according to claim 1, a receiver, a lever pivoted to the receiver, a projection on the lever adapted to engage behind the hood and lock it in its forward position, and a plug housed within the receiver and connected to the lever by a pin, in combination with a chamfered head on said plug, an extension of the barrel and a part on the barrel extension adapted to engage said chamfered head during recoil, whereby said plug is depressed to effect depression of said projection to release the hood for rearward movement.
